ROOM AIR CONDITIONER

Robert W. Blee, Louisville, Ky., assignor to General Electric Company, a corporation of New York

Filed July 1, 1958, Ser. No. 51,618

Term of patent 14 years

(Cl. D62—4)

FIG. 1

FIG. 2

FIG. 3

Fig. 1 is a perspective view of a room air conditioner embodying my new design;

Fig. 2 is a partial perspective view of the room air conditioner of Fig. 1 with the deflector panel in the open position; and

Fig. 3 is a sectional view taken along line 3—3 of Fig. 2.

The right side of said room air conditioner is the same in appearance as the left side shown in the drawing. The dominant features of the design reside in the portions shown in full line. The rear is substantially plain.

I claim:

The ornamental design for a room air conditioner, substantially as shown and described.
